SPARK-PLUG.

1,287,746.

Specification of Letters Patent. Patented Dec. 17, 1918.

Application filed May 29, 1916. Serial No. 100,472

To all whom it may concern:

Be it known that we, JULIA RAMSTACK, FRANKLIN RAMSTACK, and ERICH RAMSTACK, citizens of the United States, and residents of Milwaukee, in the county of Milwaukee and State of Wisconsin, have invented new and useful Improvements in Spark-Plugs, of which the following is a description, reference being had to the accompanying drawings, which are a part of this specification:

The invention relates to spark plugs.

The invention is designed more particularly to provide a spark plug for use in internal combustion engines of such construction as will effectually prevent the sooting of the plug.

To prevent the sooting of the plug we have provided an upper and lower chamber within the casing of the plug, the lower chamber being the ignition chamber and so constructed as to permit the spark to pass between either of two points and the upper chamber being what may be called a compression chamber to prevent the ingress of soot therein and consequently protect the portion of the plug adjacent the insulated core from short circuiting.

The invention further consists in the several features hereinafter set forth and more particularly defined by claims at the conclusion hereof.

In the drawings:

Figure 1 is a vertical sectional view through the plug embodying the invention;

Fig. 2 is a section taken on line 2—2 of Fig. 1;

Fig. 3 is a section taken on line 3—3 of Fig. 1.

In general, the spark plug comprises a casing 4 adapted to be secured to the cylinder of an internal combustion engine, an electrode 5 having a portion thereof disposed within the casing 4 and insulated therefrom and detachably connected thereto contact members 6 and 7 within the casing 4 and spaced from the lower portion of the electrode to form upper and lower spark gaps, the contact members, together with the casing 4, also forming upper and lower chambers 8 and 9 for purposes hereinafter described.

The casing 4 consists of a cylindrical member having a threaded portion 10 for detachably securing it to the cylinder of

the engine, an end portion 11 to facilitate the securing of the casing in place within said engine cylinder, an upper threaded portion 12 and a lower portion 13 provided with a plurality of apertures 14 in the sides thereof to establish communication between the interior of the cylinder and the lower chamber 9.

The electrode 5 is of usual construction consisting of a straight piece of wire which is insulated from the casing 11 by means of a core 15 of suitable insulating material, such as porcelain, the electrode extending through a cylindrical bore 16 in the core 15 and having a threaded upper end 17 for receiving the internally threaded binding post 18 and its coöperating washer 19 to which the wire, not shown, leading to a suitable source of electrical energy is connected. The electrode 16 is detachably secured within the casing 11 by means which secure the core 15 to the casing. This means consists of a nut 20 having threaded engagement with the threaded portion 12 of the casing and provided with an inwardly extending annular flange portion 21 which is adapted to engage a washer ring 22 seated on a shouldered portion 23 of the core 15 and to clamp the core 15 between the said shouldered portion 23 and the annular shouldered portion 24 in the casing which contacts with a washer 25 disposed between it and a lower shoulder 26 on the core 15. In this way the core 15 is detachably seated in the upper part of the casing and the electrode 5 carried thereby is thus properly positioned with respect to the casing.

The upper contact member 6 consists of an annular ring which rests on an annular shoulder 27 in the end portion 13 of the casing and which may be secured thereto in any suitable manner such as by punching the edges of the member 6 so as to strike up projections which engage with the interior wall of the casing. The electrode 5 runs through the opening 28 of the member 6 and is spaced therefrom so as to form the upper spark gap. The contact member 6 also serves to divide the lower part of the casing into the compartments 8 and 9.

The contact member 7 consists of an annular plate provided with a plurality of apertures 29 and seated upon inwardly extending flanges 30 at the lower end of the casing. This plate may be secured in any suitable

manner to the casing, for instance, in the same manner as that of securing the plate 6. In this connection it will also be understood that the plates 6 and 7 may be made integral 5 with the casing without departing from the spirit of the invention. The lower portion 31 of the electrode 5 projects through the opening 32 in the plate 7 and is spaced therefrom to form the lower spark gap. 10 The upper compression chamber 8 is formed by the sides of the casing, the plate 6 and the end of the core 15 and the lower ignition chamber 9 is formed by the sides of the casing and the plates 6 and 7. It will 15 be noted that the volume of the chamber 8 is greater than the chamber 9. The apertures 29 in the plate 17 and apertures 14 in the casing permit the gas to enter and escape from the chamber 9. 20 In the construction above described it will be noted that a spark may be had across the electrode 5 to the plate 6 or across said electrode to the plate 7 and in case the charge should not be fired from a spark across the plate 7, it will fire across the disk 6. The 25 apertures 14 and 29 are provided, as previously pointed out, to permit the gas to enter and escape from the lower chamber 9 and the passage of gas through said chamber 30 cleans it out and consequently keeps the lower end of the electrode clean and the plate 6 always acts to keep foreign matter away from the upper chamber. In fact, with the present construction, there is no 35 liability for any collection of soot within the chamber 8 and thus any tendency of the plug to short across the lower portion of the core 15 is prevented and the said electrode and core is kept clean. Furthermore, the 40 chamber 8 acts as a heat insulator to prevent the high explosive temperature in the combustion chamber of the engine from acting directly upon the porcelain. In case oil is used in the cylinders it frequently happens 45 that on explosion, the oil splashes up into the plug and forms a circuit across the insulation, but with the present invention the plate 6 effectually prevents this occurring for the oil can only splash up as far as the first 50 chamber and this chamber is self-cleaning by the passage of the explosive mixture therethrough. In the construction above described, attention is also called to the fact that when the explosion occurs within the 55 cylinder, the light products of combustion

pass up through the chamber 9 into the chamber 8 and forms a pressure area within said chamber 8 which prevents the heavier products of combustion from entering said chamber and through the accumulation of 60 solid matter therein short-circuiting the plug.

The invention thus exemplifies a spark plug in which the electrode passes through an upper pressure chamber and a lower ignition chamber and a plug which may be fired from two separate sources in the ignition chamber.

What we claim as our invention is:—

1. A spark plug comprising a casing having a bore therein, an insulated core having its lower end seated within the upper end of the bore, an electrode carried by said core and having a portion extending down through the bore below the core, a contact member connected to said casing within the bore and spaced from said electrode to form a spark gap, said contact member dividing said bore into an unobstructed upper pressure compartment and a lower ignition compartment, the volume of the upper compartment being greater than that of the lower compartment, a contact member at the bottom of the casing and cooperating with the electrode, and means for permitting the 85 passage of gas through the lower compartment.

2. A spark plug comprising a casing having a bore therein, an insulated core having its lower end seated within the upper end of the bore, a tubular electrode carried by said core and having a portion extending down through the bore, an annular contact plate disposed within the bore and spaced from said electrode to form a spark gap, said plate dividing said bore into an unobstructed upper pressure compartment and a lower ignition compartment, the volume of the upper compartment being greater than that of the lower compartment, and an apertured 100 plate secured to the casing and forming the lower end of the ignition compartment and spaced from the electrode to form a spark gap.

In testimony whereof, we affix our signatures.

JULIA RAMSTACK.
FRANKLIN RAMSTACK.
ERICH RAMSTACK.
